Primary Examiner — Freda S Nunn(74) *Attorney, Agent, or Firm* — Oppedahl Patent Law Firm LLC(57) **CLAIM**

The ornamental design for a tablet computer, as shown and described.

DESCRIPTION

FIG. 1 is a front view of a tablet computer showing my new design.

FIG. 2 is a left side view thereof.

FIG. 3 is a right side view thereof.

FIG. 4 is a perspective view thereof.

FIG. 5 is a perspective view thereof with the stand being in an open position.

FIG. 6 is a front view of a second embodiment thereof.

FIG. 7 is a left side view thereof.

FIG. 8 is a right side view thereof.

FIG. 9 is a perspective view thereof.

FIG. 10 is a perspective view thereof with the stand being in an open position; and,

FIG. 11 is a perspective view thereof with the stand being in second open position.

Broken lines shown in the drawings represent environment only and form no part of the claimed design and the undisclosed views do not comprise claimed subject matter.

1 Claim, 11 Drawing Sheets---
